UNITED STATES PATENT OFFICE.

JAMES WORRALL, OF ORDSALL, SALFORD, COUNTY OF LANCASTER,
ENGLAND.

APPARATUS FOR WASHING AND DYEING.

SPECIFICATION forming part of Letters Patent No. 323,095, dated July 28, 1885.

Application filed December 29, 1884. (No model.)

To all whom it may concern:

Be it known that I, JAMES WORRALL, of
Ordsall, Salford, in the county of Lancaster,
England, dyer, have invented certain new and
useful Improvements in Washing and Dyeing
Machinery, of which the following is a speci-
fication.

This invention relates to a novel arrange-
ment of machinery for subjecting pile fabrics
to a beating action while being washed or
dyed, such beating action serving, as is well
known, to prevent the lay of the pile.

In the machines hitherto constructed on the
most approved plan much difficulty has been
found in getting access to the parts, and the
cost of constructing and working such ma-
chines has been considerable. By the present
arrangement, which simplifies the construction
of the machine without detracting from its ef-
ficiency, a material economy in space is se-
cured, and all the parts are readily accessible
to the attendant.

In the accompanying drawings, Figure 1,
Sheet I, shows in longitudinal sectional eleva-
tion my improved machine for washing and
dyeing pile fabrics. In Sheet II, Fig. 2 is a
transverse vertical section of the machine;
and Figs. 3 and 4 are detached views of one of
the winces or beaters drawn to an enlarged
scale.

A A are a tank, which is to receive the cleans-
ing or the dyeing liquor, and B B are a pair of
octagonal standards, which are braced together
by cross-stays and set up on the bottom of the
tank. These standards, with their transverse
braces and vertical supports B' B', constitute
a frame for carrying the bearings for a series
of winces or beaters, C C, and a series of guide-
rollers, D D.

The bearings for the guide-rollers consist of
short pedestals set at the angles of the octa-
gon frame. At the uppermost angle, however,
the standard is branched to carry two guide-
rollers, D' D'', under which the cloth to be op-
erated upon, respectively, passes when enter-
ing and leaving the machine.

The winces or beaters are arranged in two
concentric rings, C C and C' C', around the
octagonal framing, and their bearings are car-
ried by standards made fast to the flat edges
of the octagon standards. The standards car-

rying the winces or beaters of the external
ring are higher than the standards carrying
the guide-rollers, and those carrying the bear-
ings of the inner ring of winces are shorter 55
than the guide-roller standards.

The fabric to be operated upon is led down
from an elevated guide-roller, E, into the ma-
chine under the roller D', then under the first
of the winces C, and over the first of the 60
winces C' to the second guide-roller D, over
which it passes, and so on through the whole
series of beaters and rollers until it comes to
the guide-roller D'', whence it passes to the
card-roller F, to which rotary motion is im- 65
parted for the purpose of drawing the cloth
through and out of the tank. From this draw-
ing-off roller the cloth is led past a guide-
roller, and thence to the folder G, which de-
posits it in folds upon a table, H, ready for re- 70
moval from the machine.

The winces or beaters C C' receive rotary
motion from a spur-wheel, I, keyed to a cen-
tral shaft, I', the bearings of which are carried
by the tank A and the octagon framing. Gear- 75
ing into this spur-wheel I are pinions I'', keyed
on the axles of the winces C'. These pinions
drive through pinions I''' spur-pinions I'' on the
axles of the winces or beaters C.

For driving the spur-wheel I at the requisite 80
speed, a pinion, I'', is used for transmitting the
motion thereto. This pinion is keyed to a
short shaft, I'', mounted in suitable bearings,
and carrying fast and loose band-pulleys which
receive a strap from overhead-gearing. 85

The tank, it will be seen, is of such a depth
that when fully charged with liquor one-half
only of the winces will be submerged. When,
however, it is thought desirable, the depth of
the tank may be sufficiently increased to sub- 90
merge all the winces or beaters. In such case
the winces used will be of the ordinary con-
struction; but when, as in the present instance,
one-half of the winces only are submerged,
some or all of those above the tank are made 95
to discharge liquor onto the fabric under treat-
ment. For this purpose I make the winces,
say, of the outer circle, as shown in side ele-
vation and transverse section at Figs. 3 and 4,
where c is a hollow axle receiving the deter- 100
gent or other liquor from a fixed pipe, c', in-
serted into a gland fitted in the end of the axle.

The bars c^2 of the wince or beater are made hollow, and connected by hollow arms c^3 with the axle c , which arms serve as channels for conducting the liquor from the axle to the bars c^2 . These hollow bars are slit nearly from end to end to provide a passage for the discharge of the liquor onto the cloth as it passes over them, and to prevent the closing of the slit by the cloth while held at tension over each bar of the wince in succession, ribs are formed on opposite sides of the slit to take the strain of the cloth and cause it to bridge over the slit.

15 The wince or beater is intended to discharge liquor from each bar c^2 in succession, and only at the time that the bar is in contact with the cloth. To provide for this, the fixed pipe c' , which passes from end to end of the hollow axle c , is provided with vents situate in the plane of the revolving arms c^3 . Thus, as the 20 arms severally come into coincidence with these vents, they will be supplied with liquor under pressure, which will be ejected from the slits of the bars c^2 onto the cloth in the form of intermittent jets.

25 Supposing, now, the cloth to have been led through the machine in the manner above explained, its cut pile face being outward, and rotary motion to have been imparted to the machine through the driving-pulley and spur-gearing above described, the rotary beaters C' acting upon the inner side or back of the traveling fabric, and the rotary beaters C acting on the face of the fabric, will impart to it a rapid vibratory motion, and thereby give 30 the pile a tendency to stand upright from the base of the fabric. As the beaters C and C' rotate in opposite directions they will neutralize the drag which they severally put upon the traveling fabric, and thus protect the fabric from any undue strain.

35

40

In some cases I propose to use only one series or ring of rotary beaters, which will then act upon the back of the fabric like the beaters C'.

The agitation imparted to the cloth will so 45 effectually separate the fibers of the pile as to render unnecessary much of the brushing which is at present required to raise the laid pile and to give the required finish to the fabric.

In the machine just described, washing or 50 detergent liquor or a dye-liquor may be indifferently used, so far as the action of the machine is concerned; but the manufacturer will readily understand that it is necessary to limit the use of his machinery to either the 55 washing or dyeing operation.

Having now particularly described and ascertained the nature of my said invention, and in what manner the same is to be performed, I declare that what I claim is—

In a washing and dyeing machine, the combination of a tank for containing liquor with a frame carrying a ring of guide-rollers and two rings of wincees or beaters concentric with the rollers, the guide-rollers serving to present the fabric as it is drawn through the machine to the action of the beaters, such beaters being driven in opposite directions by gearing operated from the central shaft, and serving while the cloth is presented to the action of the liquor to impart to the cloth a rapid vibratory motion, for the purpose above set forth. 65 70
